UNITED STATES PATENT OFFICE.

EDWARD P. Tabor, of Worcester, Massachusetts, assignor of one-fourth to
Herrick S. Hurlbut, of Worcester, Massachusetts.

RAIL-GRINDER.

1,260,475.

Specification of Letters Patent. Patented Mar. 26, 1918.

Application filed April 5, 1917. Serial No. 160,055.

To all whom it may concern:

Be it known that I, EDWARD P. TABOR, a citizen of the United States, residing at Worcester, in the county of Worcester and 5 State of Massachusetts, have invented a new and useful Rail-Grinder, of which the following is a specification.

The device forming the subject matter of this application is adapted to be employed 10 for grinding rails, frog-parts, mates, joints, cross-overs, switch elements and the like.

One object is to provide novel means whereby the direction of travel of a carriage which supports the grinding wheel, may be 15 reversed.

Another object of the invention is to provide novel means whereby the grinding wheel will be lifted at the time that a reversal of the carriage is brought about.

20 Another object of the invention is to provide novel means for so mounting the grinding wheel that the same will have an extended range of adjustment with respect to the work.

25 The invention aims to provide novel means for driving the carriage and to provide novel means for rotating the grinding wheel.

It is within the province of the disclosure 30 to improve generally and to enhance the utility of devices of that type to which the present invention appertains.

With the above and other objects in view which will appear as the description proceeds, the invention resides in the combination and arrangement of parts and in the details of construction hereinafter described and claimed, it being understood that changes in the precise embodiment of the 40 invention herein disclosed can be made within the scope of what is claimed, without departing from the spirit of the invention.

In the accompanying drawings:—

45 Figure 1 shows in top plan, a grinding machine constructed in accordance with the present invention;

Fig. 2 is a vertical longitudinal section taken through the mechanism which supports the grinding wheel;

Fig. 3 is an elevation showing the mechanism which supports the grinding wheel;

Fig. 4 is a perspective view delineating 55 one of the parts whereby the grinding wheel is supported;

Fig. 5 is a section taken approximately on the line 5—5 of Fig. 3;

Fig. 6 is a perspective view showing one of the slide bearings which coacts with the part shown in Fig. 4; and

Fig. 7 is a section approximately on the line 7—7 of Fig. 1.

In the accompanying drawings, the numeral 1 indicates a track, along which is adapted to reciprocate, a truck denoted generally by the numeral 2. The truck 2 may be variously constructed, but in the present instance it is shown as comprising side beams 3 and 4, an intermediate cross beam 5 connecting the side beams 3 and 4, a longitudinal beam 6 connected with the cross beam 5, cross beams 7 and 8 extended between the beam 6 and the beam 4 on opposite sides of the beam 5, arms 9 and 10 projecting from the beam 8 and connected adjacent their outer ends by a supporting rod 11, an arm 12 projecting from the beam 7, a beam 21 connecting the arm 12 with the beam 6, and a beam 32 connecting the parts 5 and 7. The particular frame-work above 75 described may, however, be changed without jeopardizing the utility of the invention.

Bearings 14 are mounted on the parts 3, 6 and 4, and in these bearings is journaled 85 a driven axle 15 carrying wheels 16 traversing the track 1. Mounted on the parts 3, 6, 12 and 4 are bearings 17 in which is journaled an idle axle 18 carrying wheels 19 traversing the track 1. A motor 20 is supported on the beams 7 and 21 and may be of any desired construction, an electric motor being delineated in the present instance. The shaft of the motor 20 appears at 22 and is journaled in a bearing 23 on the beam 6 90 adjacent the beam 21. The shaft 22 carries a worm 24 coacting with a worm wheel 25 on a shaft 26 arranged at right angles to the shaft 22, the shaft 26 being journaled in bearings 27 mounted on the beams 5 and 7. The shaft 26 is provided with a worm 28 meshing into a worm wheel 29 on a shaft 30 disposed parallel to the shaft 22 of the motor 20 and journaled in bearings 31 mounted on the beam 6 and on the beam 32. 105 By means of intermeshing beveled pinions 33, the shaft 30 is operatively connected with a shaft 34 disposed approximately parallel to the shaft 26 and journaled in bearings 35 on the beams 5 and 8. A beveled 110

pinion 36 is secured to the shaft 34 and cooperates with a reversing mechanism carried by the axle 15, and now to be described.

A sleeve 39 is splined at 40 to the axle 15 for longitudinal sliding movement thereon, and carries beveled pinions 37 and 38, adapted to coöperate one at a time with the beveled pinion 36 on the shaft 34. The numeral 41 indicates a frame supported at its 10 outer end for sliding movement on the rod 11 which connects the arms 9 and 10. At its outer side and at its extremities, the frame 41 is supplied with projections 42 and 43. The frame 41 has collars 44 slidably mounted on the axle 15, so that the frame may move longitudinally of the axle 15. The collars 44 coöperate with the ends of the sleeve 39 which carries the beveled pinions 37 and 38. Dogs 45 and 46 are pivoted at 49 to the outer ends of the arms 9 and 10 respectively, the dog 45 having an inwardly projecting finger 47, and the dog 46 having an inwardly projecting finger 48, the finger 48 being adapted to coact with a 25 projection 52 on a collar 51 slidable on the axle 15, the collar 51 constituting a part of an angular arm 50, a part of which extends approximately parallel to the axle 15. A compression spring 53 surrounds the axle 15 and is interposed between the collar 44 of 30 the frame 41 and the collar 51 of the arm 50. There are nuts 54 on the arm 50, holding adjustably on the arm, a bar 55 disposed at right angles to the axle 15 and including 35 a collar 57 slidable on the axle 15, the collar 57 having a projection 58 which coacts with the finger 47 of the dog 45. The inner end of the bar 55 is slidably supported on a wear plate 56 connected with the beam 40 8. A compression spring 59 surrounds the axle 15 and is interposed between one of the collars 44 of the frame 41 and the collar 57 of the bar 55.

A rod 60 is disposed approximately parallel to the axle 15 and is connected adjustably, by means of nuts 61, with the bar 55. Nuts 62 are employed for connecting the rod 60 adjustably with a traveler 63, with which a threaded part 64 of the axle 15 coöperates. 45 The numeral 65 marks a rod disposed approximately parallel to the rod 60 and connected adjustably, by means of nuts 66, with the traveler 63. The rod 65 terminates at one end in a vertically elongated eye 67. A 50 collar 68 is mounted on the axle 15 and includes oppositely extended projections 69 and 70 arranged approximately parallel to the axle 15. The collar 68 is frictionally held on the axle 15, and the construction is 55 such, that, although the collar 68 will rotate with the axle 15 against the action of a restraining force of considerable magnitude, a rotation of the axle 15, independently of the collar 68 withal is not impossible, when the 60 collar 68 is positively held against rotation, 65

in a manner which will be set forth hereinafter.

The numeral 71 denotes a lever passing through the eye 67 of the rod 65, the construction being such that, although the lever 71 may have a vertical movement in the eye, the eye will constitute a means for swinging the lever 71 horizontally. The numeral 72 has been used to designate a second lever, disposed at an acute angle to the lever 71. 75 The numeral 73 denotes a lever which is fulcrumed, intermediate its ends, to swing vertically on a bracket 74 carried by the beam 3. The inner ends of the levers 72, 71 and 73 are pivotally connected, as shown at 80 75, in such a way that the levers 72 and 71 cannot swing vertically, independently of the lever 73, it being possible, nevertheless, to swing the levers 71 and 72, for adjustment, in a horizontal plane, on the pivot 85 connection 75, to vary the angle between the levers 71 and 72. The vertical swinging movement of the compound lever comprising the parts 73, 72 and 71, is limited by a stop 76 which may be mounted on the beam 90 5. In order to adjust the angle between the levers 72 and 71, a bolt 77 is passed therethrough, and carries nuts 78, coöperating with the members 71 and 72. The lever 73 is provided with an extension 79. 95

The extension 79 of the lever 73 engages beneath a collar 80 secured to a screw shaft 81 provided at its upper end with a hand wheel 82, the screw shaft 81 being adapted to swing, in a direction indicated by the arrows in Fig. 2, in a slot 83 formed in a plate 84 attached to an underlying base plate 85 provided with an opening 86 which is of larger size than the slot 83 in the plate 84. The base plate 85 is pivoted as indicated at 100 87 to the beam 3, so that the base plate may be swung in a horizontal plane for adjustment, and in order to hold the base plate in adjusted positions, clamp screws 89 are inserted through arcuate slots 88 in the base plate, the clamp screws engaging the beam 3. A collar 90 is attached to the screw shaft 81 below the base plate 85, and a compression spring 91 surrounds the screw shaft, the lower end of the spring 91 engaging the collar 90, and the upper end of the spring passing through the opening 86 in the base plate 85 and bearing against the plate 84, on opposite sides of the slot 83 therein. The screw shaft 81 is threaded into a nut 92 having 105 trunnions 93 received in openings 98 formed in vertically reciprocating slide bearings 94, received in undercut guides 97 formed in vertical hangers 95 having projecting ends 96 which are secured to the under face of 115 the base plate 85. The nut 92 includes a rearwardly projecting bearing frame 99 in which is journaled a horizontal shaft 100 provided at its outer end with a grinding wheel 101, and connected at its inner end, 120 110

by means of a universal joint 102, with a telescoping or flexible shaft 103, which, in turn, is united by means of a universal joint 104, with the end of the shaft 22 of the 5 motor 20.

The drive from the motor 20 to the grinding wheel 101 includes the shaft 22, the universal joint 104, the extensible shaft 103, the universal joint 102, and the shaft 100. 10 The spring 91 maintains the grinding wheel 101 in a depressed condition, but it is obvious that if the screw shaft 81 be lifted by means of the wheel 82, the grinding wheel 101 may be adjusted vertically. Further, it is possible to swing the screw shaft 81 in the direction of the arrows in Fig. 2, the nut 92 and its frame 99 tilting, the trunnions 93 rocking in the openings 98 of the slide bearings 94, and the slide bearings 20 94 reciprocating in the guides 97 when the grinding wheel is raised and lowered as aforesaid. Further, it is possible to loosen the clamp screws 89 and to swing the base plate 85 and parts carried thereby on the 25 pivot 87, and to secure the base plate in adjusted positions by tightening down the clamp screws. In this way, the grinding wheel 101 may be adjusted laterally. The telescoping shaft 103 permits the foregoing 30 adjustments in the position of the grinding wheel 101, without destroying the operative construction between the grinding wheel and the motor 20. It will be observed that owing to the many adjustments which may be 35 made in the position of the grinding wheel 101, practically all kinds of work may be shaped properly by the grinding wheel. The drive from the motor 20 to the axle 15, to secure a reciprocating movement of the 40 truck 2 on the track 1, comprises the shaft 22, the worm 24, the worm wheel 25, the shaft 26, the worm 28, the worm wheel 29, the shaft 30, the beveled pinions 33, the shaft 34, the beveled pinion 36, and one or 45 the other of the beveled pinions 37 and 38 which are connected through the instrumentality of the sleeve 39 and the spline 40 with the axle 15, to rotate therewith, and it will be seen clearly that if an appropriate 50 mechanism is provided for bringing the beveled pinions 37 and 38 selectively into operative relation to the beveled pinion 36, a reversal in the direction of the movement of the truck 2 along the track 1 will be 55 attained.

Under normal working conditions, that is, while the truck 2 is intermediate the limits of travel on the track 1, the friction collar 68 on the axle 15, and the projections 69 on 60 the collar, are spaced from the free end of the lever 72 and from the free end of the lever 71. Assuming that the axle 15 is being driven by the pinions 36 and 37, as shown in Fig. 1, the thread 64 on the axle 65 15 advances the traveler 63, and the eye 67

on the rod 65, coacting with the lever 71, tilts the lever 71 and the lever 72, in fixed angular relation to each other, on the pivotal connections 75, in a horizontal plane, until the outer end of the lever 71 lies in 70 the path of the projection 69 on the collar 68. Since the collar 68 is frictionally held to the axle 15, the collar 68 will rotate, for a time, along with the axle 15, until the finger 69, pressing on the end of the lever 75 71, tilts the lever 71 and the lever 73 on the fulcrum 74, the lever 73 moving upwardly, in a vertical direction, and the extension 79 of the lever 73, being engaged beneath the collar 80 on the screw shaft 81, 80 serving to elevate the screw shaft 81 and the grinding wheel 101, the slide bearings 94 moving upwardly in the guides 97. In this way, a lifting of the grinding wheel 101 is brought about, at the time that the 85 direction of travel of the truck 2 on the track 1 is reversed. After the lever 73 has engaged the stop 76, when the lever 73 is tilted vertically as aforesaid, the vertical 90 tilting movement of the lever 73 and consequently that of the lever 71 is positively arrested, and the axle 15 then rotates in the collar 68, the latter being frictionally held to the axle, as aforesaid, the projection 95 59 remaining in engagement with the free end of the lever 71.

When the traveler 63 is advanced by the threaded portion 64 of the axle 15, as above described, the rod 60 advances the cross bar 55, and the cross bar advances the angular 100 arm 50, the collar 51 of the arm compressing the spring 53 against the corresponding collar 44 or the frame 41. The projection 52 on the collar 51 of the arm 50 engages the finger 48 of the dog 46 and tilts the dog 105 on its pivot 49, thereby disengaging the dog from the projection 43 on the frame 41. The frame 41 now moves to the left (Fig. 1) under the action of the spring 53, the pinion 37 being disengaged from the pinion 110 36, and the pinion 38 is coupled up with the pinion 36, thus securing a reversal in the direction of the rotation of the axle 15, and it is at the time of this reversal, that the grinding wheel 101 is elevated as aforesaid, the elevation of the grinding wheel, at 115 the time of reversal, preventing a gouging or other injury to the work.

When the frame 41 moves to the left as above described under the action of the 120 spring 53, the projection 42 on the frame engages with the dog 45. Since the direction of rotation of the axle 15 has been reversed, because the beveled pinion 36 has been engaged with the beveled pinion 38, the 125 traveler 63 will move to the right (Fig. 1) along the screw 64. The eye 67 on the rod 65 tilts the lever 71 out of engagement with the finger 69 of the collar 68, the latter rotating then with the axle 15, and the lever 73 130

swinging downwardly, permitting a lowering of the grinding wheel 101. As the traveler 63 continues to move to the right (Fig. 1) and the projection 70 on the collar 68 ultimately engages with the free end of the lever 72, and the operation above described is reversed at the opposite end of the stroke or travel of the truck, the spring 59 is compressed, the projection 58 on the collar 57 coacting with the finger 47 of the dog 45 disengaging the dog 45 from the projection 42 on the frame 41, and the frame 42, moving to the right (Fig. 1) lies in the position of Fig. 1, the pinion 37 then being coupled up with the pinion 36.

The distance which the truck 2 travels along the track 1 at each stroke may be varied by adjusting the angle between the levers 71 and 72, this result being brought about by shifting the nuts 78 on the bolt 77, further adjustments being made by shifting such parts as the nuts 61 and 62, and the nuts 54, in order to position the traveler 63, the cross bar 55 and the angular arm 50 properly with respect to each other.

Having thus described the invention, what is claimed is:—

1. In a device of the class described, a truck; a grinding member; means for mounting the grinding member on the truck for movement into and out of relation to the work; means for driving the truck; a reversing device connected with the driving means; and mechanism operatively connected with the reversing device and with the grinding member for moving the grinding member out of operative relation to the work when the reversing device changes the direction of travel of the truck.
2. In a device of the class described, a truck; a grinding member; means for mounting the grinding member on the truck for movement into and out of operative relation to the work; a lever fulcrumed on the truck and coacting with the grinding member to move the same out of operative relation to the work; means for driving the truck, said means including a shaft; a reversing device connected with the driving means; a friction member on the shaft and coacting with the lever to move the grinding member out of operative relation to the work; and mechanism operatively connected with the reversing device and with the lever to move the lever into the path of the friction member when the reversing device changes the direction of travel of the truck.
3. In a device of the class described, a truck; a grinding member; means for mounting the grinding member on the truck for movement into and out of operative relation to the work; a lever fulcrumed on the truck for swinging movement in one plane and coöperating with the grinding member; arms pivoted to the lever for swinging

movement in a different plane; means for adjustably connecting the arms to vary the angle therebetween; a driving means for the truck and comprising parts wherewith the arms coact respectively; a reversing device connected with the driving means; and a connection between the reversing device and one arm for moving the arms respectively into the path of said parts when the reversing device changes the direction of travel of the truck.

4. In a device of the class described, a truck; a grinding member; means for mounting the grinding member on the truck for raising and lowering, and for swinging movement under the control of an operator in a substantially vertical plane; means for driving the truck; a reversing device connected with the driving means; and mechanism operatively connected with the reversing device and with the grinding member for raising and lowering the grinding member when the reversing device changes the direction of travel of the truck.

5. In a device of the class described, a truck; a grinding member; means for mounting the grinding member on the truck for raising and lowering, and for adjustment about a substantially vertical axis; means for driving the truck; a reversing device connected with the driving means; and mechanism operatively connected with the reversing device and with the grinding member for raising and lowering the grinding member when the reversing device changes the direction of travel of the truck.

6. In a device of the class described, a truck; a grinding member; means for mounting the grinding member on the truck for raising and lowering, for adjustment about a substantially vertical axis, and for swinging movement in a substantially vertical plane; means for driving the truck; a reversing device connected with the driving means; and mechanism operatively connected with the reversing device and with the grinding member for raising and lowering the grinding member when the reversing device changes the direction of travel of the truck.

7. In a device of the class described, a truck; a bearing mounted to reciprocate in a substantially vertical direction on the truck; means for raising and lowering the bearing; a carrier mounted to tilt in a substantially vertical plane on the bearing; a shaft journaled for rotation in the carrier; a grinding member carried by the shaft; and truck carried means for rotating the shaft.

8. In a device of the class described, a truck; a hanger carried by the truck; a slide mounted to reciprocate in a substantially vertical direction in the hanger; a nut pivoted to the slide for swinging movement in

a substantially vertical plane; a shaft journaled in the nut; a grinding member carried by the shaft; means on the truck for rotating the shaft; a screw threaded into the nut and mounted to swing with respect to the truck; and mechanism for limiting the longitudinal movement of the screw with respect to the truck.

In testimony that I claim the foregoing as my own, I have hereto affixed my signature in the presence of two witnesses.

EDWARD P. TABOR.
